CLAIM

The ornamental design for the water kettle, as shown and described above.

DESCRIPTION

FIG. 1 is a perspective view of a water kettle showing our new design;

FIG. 2 is a front plan view of the water kettle shown in FIG. 1;

FIG. 3 is a rear plan view of the water kettle shown in FIG. 1;

FIG. 4 is a side elevational view of the water kettle taken from the left of FIG. 1;

FIG. 5 is a side elevational view of the water kettle taken from the right of FIG. 1;

FIG. 6 is a top plan view of the water kettle; and,

FIG. 7 is a bottom plan view of the water kettle in FIG. 1.
